UNITED STATES PATENT OFFICE.

FRANK A. FLETCHER, OF WATERTOWN, NEW YORK, ASSIGNOR TO THE
AERATED PAPER COMPANY, OF NEW YORK, N. Y.

PROCESS OF PAPER MANUFACTURE.

SPECIFICATION forming part of Letters Patent No. 645,080, dated March 13, 1900.

Original application filed April 20, 1899, Serial No. 713,699. Divided and this application filed June 26, 1899. Serial No. 721,810. (No specimens.)

To all whom it may concern:

Be it known that I, FRANK A. FLETCHER, a citizen of the United States, residing at Watertown, Jefferson county, New York, have 5 invented certain new and useful Improvements in Processes of Manufacturing Paper, of which the following is a full, clear, and exact description.

This invention relates to the manufacture 10 of paper, and particularly to a new process therefor, this application being a division of a former application serially numbered 713,699, filed April 20, 1899.

The object of this process is to obtain a 15 product of a soft, porous, and highly-absorbent nature.

In describing the process I will briefly allude to an apparatus (such as described in detail in the referred-to original application 20 of which this is a division) as illustrative of one form of apparatus by which such paper may be produced. To that end, therefore, the accompanying drawing illustrates a vertical sectional view of a preferred form of 25 apparatus, parts of the same being only indicated.

The product in this process may be made from almost any kind of stock possessing a suitable fiber, especially "soda-pulp." The 30 fiber is reduced to a pulp, and as I desire to produce a paper which is soft and extremely porous I prefer not to subject the pulp to pressure before I treat it, as hereinafter described.

35 In the accompanying drawing I have shown the sheet of paper formed by a "cylinder-machine," but do not desire to limit myself to that method of forming the sheet.

A is a vat that contains paper-pulp, *a* being an inlet for the same, and *a'* an outlet for the water from a revolving cylinder-mold B. This mold is preferably hollow and covered with wire-cloth or other suitable material, and upon it is deposited the paper strip or 45 pulp in the well-known manner.

C is a couch-roll, and D a roll over which and over suitable intermediate supporting or carrying rolls *d d* may pass a conveyer-belt E, preferably in the form of an endless strip 50 of wire-cloth or other suitable material.

The rolls C and D and cylinder-mold B are suitably rotated in the direction of the arrows. The paper-pulp strip is formed upon the mold B and taken up by the wire-cloth in the manner understood in this art and 55 carried by it in the form of a continuous strip F of the desired thickness.

When I speak of a "strip of paper-pulp," I do not mean that the pulp must necessarily be made from paper, but only that it is a pulp 60 which will form a paper, and, further, I do not mean that the paper of the strip must necessarily be in the condition that it is when it comes from the cylinder-mold; but this latter or substantially this is preferable. 65

The wire-cloth belt allows some of the water in the strip to drain away, and the belt preferably passes over suction-boxes G G, which extract from the strip a portion of the remaining moisture. The belt may then pass 70 over a suitable drying means, such as heating-boxes H, located in any suitable position and heated by any suitable means. After leaving the roll D the paper may pass to a conveyer K and out through an air-lock aperture 75 L to rolls M, if desired. As the wire-cloth belt and the strip of paper pass the heating-boxes the paper will be partially dried.

To accelerate this drying and to produce other advantageous results, I subject the paper 80 strip while still moist to the action of a rarefied atmosphere and preferably to heat at the same time. This may be accomplished by passing the strip through a heated chamber from which the air has been exhausted to any 85 desired degree. As the paper strip comes wet or moist from the vat, I rarefy the air within the chamber by any suitable means—for example, the pump O—thus lowering the 90 boiling-point of the water in the strip, and as said strip passes the heating-boxes this water or some of it is preferably turned into steam bubbles, which force apart the particles of the paper strip and which, if the heat is continued, finally evaporate, producing an extremely soft, porous, and highly-absorbent 95 product.

It is not necessary in forming a soft, porous, and highly-absorbent paper by my process that the heat should be so great as to con- 100

vert the water in the strip into steam, because if the heat is only enough to evaporate the water without first converting it into steam a paper will result having these characteristics to 5 a certain extent; but the paper will not be so porous as it would be if the water were converted into steam, as aforesaid. One important advantage of rarefying the air in the heating-chamber is that such a high degree of heat 10 is not required to convert the water in the strip into steam or to otherwise evaporate it as would otherwise and usually be the case. This materially lessens the danger of injuring 15 the paper strip by a too-great degree of heat, which might degrade the color or strength of the product. In this way I can produce, if desired, a continuous strip of soft and extremely-porous, consequently highly-absorbent, paper without resorting to the 20 common expedient of compression. The process, therefore, mainly consists in forming a sheet of moist paper-pulp within a substantially-closed chamber and of rarefying and heating the air around the sheet to drive off 25 some of the moisture therefrom.

It will be obvious that many changes may be made in the process herein disclosed without departing from the spirit of my invention.

What I claim is—

- 30 1. The process of manufacturing paper which consists in forming a sheet of moist paper in a substantially-closed space and rarefying and heating the air in said space to drive off some of the moisture from said sheet, thereby producing a soft and porous paper.
- 35 2. The process of manufacturing paper which consists in forming a sheet of moist paper-pulp in a rarefied atmosphere and heat-

ing the same to drive off some of the moisture therefrom to substantially dry said strip without substantial compression, thereby producing a soft and porous paper. 40

3. The process of manufacturing paper which consists in forming a strip of moist paper-pulp in a rarefied atmosphere and heating the same to assist in driving off the moisture from said strip, and substantially drying said paper without substantial compression of the same, thereby producing a soft and porous paper. 45

4. The process of manufacturing paper which consists in forming a strip of moist paper-pulp in a rarefied atmosphere, applying heat to the same to drive off some of the moisture therefrom, and passing said sheet back and forth through said heated and rarefied atmosphere to substantially dry said strip without substantial compression of the same, thereby producing a soft and porous paper. 55

5. The process of manufacturing paper which consists in forming a continuous strip of moist paper-pulp in a rarefied atmosphere, extracting by suction some of the moisture from said strip, applying heat to said strip to drive off some of the moisture therefrom, and passing said strip through said heated and rarefied atmosphere until the same is substantially dry, without substantial compression of the same, thereby producing a soft and porous paper. 60

Signed at New York, N. Y., this 21st day of June, 1899.

FRANK A. FLETCHER.
